UNITED STATES PATENT OFFICE.

ANTONEY M. OLSEN, OF VALLEY CITY, NORTH DAKOTA.

DESIGN FOR A HEATING-DRUM.

SPECIFICATION forming part of Design No. 25,200, dated February 25, 1896.

Application filed January 20, 1896. Serial No. 576,252. Term of patent 14 years.

To all whom it may concern:

Be it known that I, ANTONEY M. OLSEN, a citizen of the United States, residing at Valley City, in the county of Barnes and State of North Dakota, have invented a certain new and original Design for Heating-Drums; and I do declare the following to be a full, clear, and exact description of the invention, such as will enable others skilled in the art to which it appertains to make and use the same, reference being had to the accompanying drawing, and to the letters of reference marked thereon, which form a part of this specification.

My new and original design has for its object to give to a heating-drum a novel, distinctive and pleasing appearance.

A drum made according to my design is illustrated in the accompanying drawing, which shows a heating-drum in perspective view.

The characteristic features of my design are the boxes or drum-sections A, connected by the flues or pipes B. There are a plural-

ity of these boxes A and a plurality of sets 25 of flues B. Each box is circular in outline, is comparatively shallow and has flat ends a. The boxes A are arranged in line with each other and separated, as indicated in the drawing, the adjacent boxes being connected each 30 by a set of flues B, which flues are circular in outline. As shown, each set contains eight flues. The flues B are disposed in a circle concentric with the boxes A to which the set is connected. The lower box A is provided 35 with the legs C, upon which the heating-drum as a whole rests.

What I claim, and desire to secure by Letters Patent, is—

The design for heating-drums, substantially 40 as shown and described.

In testimony whereof I affix my signature in presence of two witnesses.

ANTONEY M. OLSEN.
